United States Patent Office.

CHARLES H. AMIDON, OF GREENFIELD, MASSACHUSETTS.

Letters Patent No. 64,931, dated May 21, 1867.

IMPROVEMENT IN BRACES FOR BITS.

The Schedule referred to in these Letters Patent and making part of the same.

TO ALL WHOM IT MAY CONCERN:

Be it known that I, CHARLES H. AMIDON, of Greenfield, in the county of Franklin, and State of Massachusetts, have invented a new and useful Improvement in Bit-Braces; and I do hereby declare the following to be a full, clear, and exact description of the same, reference being had to the accompanying drawings, in which—

Figure 1 is a side elevation of this invention.

Figure 2 is a front view of the socket.

Figure 3 is an elevation of the clamping device.

Figure 4 is a perspective view of the socket with clamping device in position.

The object of my invention is to produce a bit-brace with a socket for the shank of a bit, so constructed that said shank may be inserted beneath a clamping-stirrup, and not only prevented from turning within said stirrup and socket, but by a shoulder projecting in front of the shoulder of the shank, the same may be prevented from slipping out of the socket.

That others may understand the construction and operation of my invention, I will particularly describe it.

A is the shank of the brace in which is formed the half-socket D. The form of the shank A is clearly shown in fig. 1. The half-socket D is a tapering groove formed in the flat surface of the shank A, its re-entrant angle being a right angle, and its taper being such as will correspond to the general taper of bit-shanks. Through the shank A, transverse to the half-socket D, is a deep recess, b, shown in fig. 2, the centre of which penetrates entirely through the shank. Within this recess is placed the stirrup B, which is constructed with a rectangular orifice E penetrating through it transversely, the angle F being made accurately a right angle. This stirrup is also provided with a screw-shank, H, which projects through the orifice at the bottom of the recess b, and upon which the thumb-nut C is placed. At the larger end of the half-socket is a small projecting shoulder, G, placed directly in the angle to prevent the shank of a bit, when once placed in the half-socket D and clamped there, from being pulled out and detached, as this shoulder then lies directly in front of the shoulder at one corner of the shank.

The operation of this device is very simple and perfectly effective, while in construction is very cheap and unlikely to be deranged. The thumb-nut C being loosened or run back upon the shank H, permits the stirrup B to be raised out of the recess b, and expose more or less of the orifice E. A bit-shank of any size (within the capacity of the implement) may be introduced through the orifice E, and placed in position within the half-socket D, the sides of which being at right angles to each other fit two of the sides of the socket. The bit-shank must be introduced far enough to bring the shoulder in front of its shank behind the shoulder G and in contact with it. When the bit-shank is in this position the sides of the half-socket D, in contact with two of the sides of the bit-shank, the two sides of the orifice E which join at F will embrace the two opposite sides of the same shank, and as the thumb-nut C is screwed down upon the shank H, the bit-shank will be drawn tight against the sides of the half-socket D, and firmly held while the bit is being rotated by the brace, and the shoulder G will effectually prevent the withdrawal of the bit in the line of its axis without loosening the stirrup.

Having described my invention, what I claim as new, and desire to secure by Letters Patent, is—

The combination of the clamping-stirrup B and shoulder G in the shank of a bit-brace, for the purpose set forth.

CHARLES H. AMIDON.
